UNITED STATES PATENT OFFICE.

ARNOLD CHRISTIANSON, OF DETROIT, MICHIGAN.

MILL FOR ROLLING TAPERED DISKS.

1,399,333.

Specification of Letters Patent.

Patented Dec. 6, 1921.

Application filed July 21, 1920. Serial No. 397,956.

To all whom it may concern:

Be it known that I, ARNOLD CHRISTIANSON, a resident of Detroit, in the county of Wayne and State of Michigan, have invented a new 5 and useful Improvement in Mills for Rolling Tapered Disks, (Case 1,) of which the following is a specification.

The invention relates to rolling apparatus designed particularly for converting metallic 10 cup-shaped blanks into disks which are of decreasing thickness from near their central portions to their peripheries.

In my application of even date herewith, Serial No. 397,958, is described a method of 15 forming disks for steel wheels, such as largely used on motor cars, and of decreasing thickness from near their centers to their peripheries, said method consisting in taking a circular metal plate, forming it into a 20 deep substantially cylindrical cup, preferably by punching through a die or dies, and then subjecting the walls of the cup to a rolling action, applied circumferentially thereof in a manner to produce the greatest 25 reduction at the open end of the cup and gradually decreasing toward its bottom, thereby expanding the blank circumferentially, progressively through different stages 30 of flare, into a substantially flat disk which tapers from near its center to its periphery.

The apparatus of this application is designed particularly for converting such metallic cups into disk form.

In the accompanying drawings Figure 1 35 is a plan view of the machine; and Fig. 2 is a longitudinal section on the line 2—2, Fig. 1.

In the drawings 1 indicates the cup-shaped blank to be reduced to disk form. 2 and 3 are the reducing rolls, preferably of conical 40 form as shown and mounted in suitable bearings with their axes converging and forming therebetween the pass in which the wall of the cup-shaped blank is reduced, one of the rolls entering into the cup as illustrated. The rolls are so arranged as to exert 45 the greatest reduction at the open end of the cup, with decreasing reduction toward its bottom, and means are provided for adjusting one of the rolls so as to progressively 50 reduce the thickness of the cup wall at its open end, as the reduction progresses. To this end the shaft of one of the rolls, such as the shaft of the roll 2, is mounted in stationary bearings 5, secured at 6 to the main 55 frame 7 of the machine, while the shaft of roll 3 is mounted in bearings 8 on an adjust-

able carrier 9, movable on the main frame in an arcuate path, being centered at the point 10 so that the free or smaller end of the roll 3 has very slight movement during 60 the adjustment. The outer end of the carrier 9 is guided by the arc-shaped thrust bearing 11, provided with rollers 12 or the like for reducing friction. Any suitable means may be used for adjusting this carrier, 65 the drawings showing a screw 13, provided with hand wheel 14. By rotating this screw as the reduction progresses, the angular position of the shaft of roll 3 is varied thus bringing the base of the roll 3 closer and 70 closer to the base of roll 2 and progressively thinning the blank at its free edge.

The rolls 2 and 3 can be driven by any suitable means, the drawings showing for this purpose pulleys 15 and 15^a on the respective shafts of said rolls, for receiving belts from any suitable driving source.

Means are provided for holding the cup against endwise displacement from the rolls 2 and 3. The holding means illustrated comprises a disk 16 adapted to engage the bottom of the cup and preferably secured thereto by means of a washer 17 inside of the cup and a screw 18, passing through said washer and through a hole formed centrally in the 80 bottom of the cup and entering the disk 16. This disk 16 is provided with a shaft 19 rotatably mounted in a bearing 20, preferably on roller bearings 21 to reduce friction, so as to allow free rotation of the cup-shaped 90 blank. This retaining means is mounted on a carriage 22, which is longitudinally movable in the main frame 7, being guided therein in suitable ways, much like the ways of a shaper carriage and adapted to be moved toward and from the rolls 2 and 3 by any suitable means, the drawings showing for this purpose a shaft 23 mounted in the main frame and provided with a hand wheel 24 on its outer end and at its inner end with a pinion 25 engaging a rack 26 on the carriage 22. This carriage will be moved away from the rolls to receive a cupped blank, then moved toward the rolls to properly position the walls of the cupped blank between the rolls, 100 and then remains stationary during the rolling operation.

The rolls 2 and 3 exert a rolling action circumferentially on the walls of the cupped blank 1 with the greatest reduction at the 110 open end of the cupped blank and the amount of reduction gradually decreasing

toward the bottom of the blank, where it is zero. The effect of this is to cause the cup to flare at its open end, the flaring progressively increasing as the reduction continues under the above described feeding action of the roll 3 toward the roll 2. The result is that the bottom of the cup begins to take an angular position relative to the wall which is gripped in the 10 pass of the rolls, such angular position progressively increasing until said bottom comes substantially in line with the said wall of the cup, at which stage the cup has been converted into a substantially flat 15 blank. To compensate for this the retaining means 16 and its associated parts must change their position to correspond with the change of the position of the bottom of the cup as the reduction progresses. To this 20 end the bearing 20 is formed on the upper part of a carrier 28 which has an oscillatory movement on the carriage 22, being pivotally mounted thereon, by the pivot pin 29, which is co-incident in this instance with 25 the axis 10 about which the roll carrier 9 pivots, but in a higher plane. The outer end 30 of the carrier 28 is formed on the arc of a circle struck about the center 29 and is guided by an overhanging thrust bearing 31 30 on the carriage 22, which bearing, or the outer portion of the carrier 28, is provided with rollers or the like 32 to reduce friction to a minimum, so that said carrier 28 automatically shifts its angular position due to 35 the pressure exerted by the change of angular position of the bottom of the cup-shaped blank, as above described. At the end of the rolling operation, that is when the blank has been converted into a substantially flat 40 disk, the axis of the shaft 19 of the retaining disk 16 lies in the dotted line position shown in Fig. 1, substantially at right angles to its original position. The carrier 28 is preferably provided with a handle 33 for 45 swinging said carrier back to original position when receiving a new blank.

The action of the apparatus described stretches the metal circumferentially of the blank, with practically no stretching or expansion radially of the completed disk, with 50 the result that the cup-shaped blank is converted into a disk whose radius is substantially equal to the depth of the cup, plus one-half of the diameter of the bottom of the cup. As a consequence the metal is not put in strain, is perfectly smooth and free 55 from waves, and there are no radial cracks, or strains tending to produce radial cracks, such as occur when a flat blank of uniform thickness is changed to tapering thickness 60 toward its periphery and of greater diameter than the original blank. With the mill described there is practically no working or stretching of the metal in a direction radially to the finished blank, but all of the 65

stretching is at right angles to such radius.

The details of the apparatus described may be varied within wide limits. In a machine where a large out-put is sought, automatic mechanism can be substituted for 70 the screw 13 for progressively adjusting the angular position of the roll 3 during the rolling, and for quickly opening up the rolls to receive a new blank, and suitable power mechanism, such as an air or hydraulic 75 cylinder, may be substituted for the rack and pinion means illustrated for moving the carriage 22 back and forth, in order to secure a quicker movement of the carriage, 80 where speed is desired.

I claim:

1. In an apparatus for converting metallic cups into disks, the combination of rolls arranged one to bear on the inside and the other on the outside of the cup and receiving the cup walls therebetween, said rolls being arranged to exert the greatest rolling action on the cup walls at the open end and a gradually reducing rolling action toward the bottom thereof, and means engaging the 90 bottom of the cup and holding the same in position between the rolls, said means being arranged to vary its angular position in relation to the pass between the rolls as the cup is progressively flared. 95

2. In an apparatus for converting metallic cups into disks, the combination of rolls arranged one to bear on the inside and the other on the outside of the cup and receiving the cup walls therebetween, said rolls being arranged to exert the greatest rolling action on the cup walls at the open end and a gradually reducing rolling action toward the bottom thereof, means engaging the bottom of the cup and holding the same in position between the rolls, said means being arranged to vary its angular position in relation to the pass between the rolls as the cup is progressively flared and means to adjust said rolls to vary the rolling pressure 105 to a greater extent at the open end of the cup than toward its bottom. 110

3. In an apparatus for converting metallic cups into disks, the combination of rolls arranged one to bear on the inside and the other on the outside of the cup and receiving the cup walls therebetween, said rolls being arranged to exert the greatest rolling action on the cup walls at the open end and a gradually reducing rolling action toward 115 the bottom thereof, and rotary means engaging the bottom of the cup and holding the same in position between the rolls, said means being automatically movable to vary the relation of its axis to the pass between 120 the rolls. 125

4. In an apparatus for converting metallic cups into disks, the combination of rolls arranged one to bear on the inside and the other on the outside of the cup and receiving 130

the cup walls therebetween, said rolls being arranged to exert the greatest rolling action on the cup walls at the open end and a gradually reducing rolling action toward the bottom thereof, and means engaging the bottom of the cup and holding the same in position between the rolls, said means being automatically movable by the pressure of the cup bottom to automatically assume the position which said cup bottom takes.

5 5. In an apparatus for converting metallic cups into disks, the combination of rolls arranged one to bear on the inside and the other on the outside of the cup and receiving the cup walls therebetween, said rolls being arranged to exert the greatest rolling action on the cup walls at the open end and a gradually reducing rolling action toward the bottom thereof, and means engaging the 10 bottom of the cup and holding the same in position between the rolls, said means being rotatable on an axis substantially parallel to the roll pass and being automatically movable to vary its axis to a position substantially at right angles to the axis of the roll pass.

6 6. In an apparatus for converting metallic cup-shaped blanks into disks, the combination of rolls arranged one to bear on the inside and the other on the outside of the cup and reducing the cup walls therebetween and arranged to exert the greatest reducing action on the cup walls at the open end and a gradually decreasing reducing action toward the bottom of the cup, and rotary means engaging the bottom of the cup and holding the same in position between the rolls, said means being mounted on a carriage movable toward and from the rolls in 15 the general line of their axes and being ar-

ranged to vary its angular position in relation to the pass between the rolls as the cup is progressively flared.

7 7. In an apparatus for converting metallic cup-shaped blanks into disks, the combination of rolls arranged one to bear on the inside and the other on the outside of the cup and to reduce the cup walls therebetween and arranged to exert the greatest rolling action on the cup walls at the open end and a gradually decreasing reducing action toward the bottom thereof, means engaging the bottom of the cup to hold the same in position between the rolls, said means being arranged to automatically vary its position according to the position assumed by the bottom of the cup-shaped blanks.

8 8. In an apparatus for converting metallic cup-shaped blanks into disks, the combination of a rotatable retainer against which the cup is held by its bottom, rolling means engaging the walls of the cup-shaped blank from the open end thereof and arranged to exert an expanding action on the walls of the cup greatest at its open end and gradually decreasing toward its bottom, means for gradually varying said expanding action as the walls of the cup decrease, and a support for said rotary retainer arranged to permit the same to shift the axis of the retainer from a position substantially parallel to the roll pass to a position substantially at right angles thereto.

In testimony whereof I have hereunto set my hand.

ARNOLD CHRISTIANSON.
